A. H. GREBE.

RECEIVING APPARATUS FOR RADIO TRANSMISSION SYSTEMS.

APPLICATION FILED NOV. 2, 1914.

1,193,778.

Patented Aug. 8, 1916.

UNITED STATES PATENT OFFICE.

ALFRED H. GREEBE, OF RICHMOND HILL, NEW YORK, ASSIGNOR TO EUGENE B. MILLER,
OF RICHMOND HILL, NEW YORK.

RECEIVING APPARATUS FOR RADIO TRANSMISSION SYSTEMS.

1,193,778.

Specification of Letters Patent. Patented Aug. 8, 1916.

Application filed November 2, 1914. Serial No. 869,783.

To all whom it may concern:

Be it known that I, ALFRED H. GREEBE, a citizen of the United States, residing at and whose post-office address is No. 10 Van Wyck avenue, Richmond Hill, county of Queens, State of New York, have invented certain new and useful Improvements in Receiving Apparatus for Radio Transmission Systems; and I do hereby declare the following to be a full, clear, and exact description of the invention, such as will enable others skilled in the art to which it appertains to make and use the same.

This invention relates to receiving apparatus for radio transmission systems. It is of special utility in a receiver for a wireless telegraph system although it may also be used in systems of wireless telephony.

The invention is directed to the provision of a receiving apparatus which is of simple construction, which may be manufactured at low cost, which occupies but little space and with which the sounds of the received signals are amplified or intensified to such an extent that they may be heard at a distance from the receiving apparatus and without holding a portion of the apparatus to the ear.

In receiving apparatus for wireless telegraph systems, it has been common heretofore to utilize a telephone receiver connected in the receiving circuit and to hold this receiver close to the ear in order to hear the sounds which are quite faint because of the low value of the current variations which cause the signals. It is highly desirable that the signals received in such a system should be amplified or intensified not only so that they may be more readily heard and heard without the necessity of holding a portion of the receiving apparatus to the ear, but also in order to more effectually guard against the loss of signals.

In accordance with the present invention, a simple form of apparatus is provided whereby the sounds of the received signals may be amplified to such extent as to enable the operator to hear them quite clearly at a substantial distance from the apparatus.

The invention involves the provision of an electric telephone receiver adapted to be connected in the receiving circuit of the system and a microphone mounted opposite the telephone receiver so that the diaphragms of the two instruments are opposed one to

the other. Preferably the telephone receiver and the microphone are so secured together that a closed chamber is provided between them, the diaphragms of the two instruments being parallel and opposite to each other on opposite sides of this closed chamber. Because of the fact that the chamber is closed, foreign sounds are more effectually excluded and the diaphragm of the microphone will vibrate in exact correspondence with the vibrations of the diaphragm of the telephone receiver. In order to secure the best results under the variable conditions incident to the use of wireless telegraph apparatus, the combined telephone receiver and microphone are so mounted as to permit of varying their angular disposition. By reason of this provision, it is possible to adjust the microphone to such an angular position as is found by experiment to make it most sensitive under the prevailing conditions. The microphone thus arranged is connected in circuit with a battery and a low resistance telephone receiver so that it controls the current flowing in the circuit of this receiver which latter serves to reproduce the received signals and intensify the sound thereof to such extent that they may be heard distinctly at a substantial distance.

I have illustrated the preferred embodiment of my invention in the accompanying drawings, in which—

Figure 1 is a front view of the apparatus, broken away in part, with the circuit connections shown diagrammatically, and Fig. 2 is an enlarged sectional view of the pivotally mounted, combined telephone receiver and microphone.

Referring to these drawings, the apparatus is shown as mounted within a rectangular casing 3 on which two binding-posts 4 are mounted adapted to receive the wires connecting the instrument in the receiving circuit of the system. In Fig. 1 the receiving circuit of a wireless telegraph system is illustrated diagrammatically, this including an aerial 5 which is connected to the ground through the primary 6 of an oscillation transformer. The secondary 7 of this transformer is connected in circuit with a condenser 8 and the wires 9 and 10 which are connected to the binding-posts 4 are connected to opposite sides of the condenser 8.

2

Within the casing 3 is a combined telephone receiver and microphone, these being so mounted as to permit of angular adjustment of their position. The telephone receiver consists of a casing 11 having a diaphragm 12 mounted therein and vibrated by electro-magnets 13 whose coils are connected to binding-posts 14 projecting through the casing 11. These binding-posts 10 are connected by wires 53 to the binding-posts 4. The casing of the telephone receiver has an opening in the front thereof as shown in Fig. 2 and this opening is in alinement with an opening in the front-piece 15 of the casing of the microphone. This piece 15 lies against the face of the casing 11 of the telephone and is secured thereto by screws 16. In this way a closed chamber is provided between the diaphragm 12 of the telephone receiver and the diaphragm 17 mounted within the casing of the microphone so that sound waves emanating from sources exterior to the two instruments are practically negligible in their effect upon the diaphragms of the instruments. The back-piece 18 of the casing for the microphone has a carbon block 19 secured thereto by a screw 20 but insulated therefrom by the interposition of suitable 25 insulating material 21. This carbon block has a plurality of cups or depressions formed in one face thereof which face lies very close to the diaphragm 17. These cups or depressions form receptacles in which a 30 pulverulent material 22 such as granular carbon is inserted, each of the depressions being but partially filled by the powdered substance. On the piece 18 of the casing of the microphone are two binding-posts, one 35 of which, indicated at 23, is insulated from the piece 18. This binding-post 23 is connected by a wire 24 with the carbon block 19. The other binding-post 25 is in electrical connection with the casing of the microphone and hence with the diaphragm 17 thereof. The telephone receiver and microphone thus combined are pivotally mounted so that they may be moved to various angular positions. For this purpose a supporting strip 26 is secured to the casing 11 of the telephone and has trunnions 27 and 28 secured to it in axial alinement. The end of the trunnion 28 is received in a bearing 29 on the casing 3 and the trunnion 27 extends through a bearing in the opposite wall of the casing 3 and has an operating handle 30 secured thereto. This trunnion 27 also has an index 31 secured to it and adapted to move over a scale 32 provided 40 upon the face of the casing 3.

Within the casing 3 is a battery preferably consisting of a plurality of cells, three cells being shown in the present instance, as indicated at 33, 34 and 35. On the face of 45 the casing is a pivotally mounted switch

arm 36 operated by a handle 37 and adapted to contact with any one of three studs, a dead stud 38 and studs 39 and 40, which are connected to the batteries 34 and 33 respectively. The batteries 33 and 34 are connected together as shown at 41 and the batteries 34 and 35 are connected together as shown at 42.

70 Two binding-posts 43 and 44 are provided upon the face of the casing, the post 43 being connected to the battery 35 by wire 45 and the post 44 being connected to the binding-post 25 of the microphone by wire 46. The other binding-post 23 of the microphone is connected by wire 47 to the switch 80 arm 36.

With the apparatus thus constructed and arranged the variations of current in the receiving circuit of the wireless system vary the magnetic effect of the magnets 13 upon 85 the diaphragm 12 so as to cause vibration of that diaphragm. These vibrations cause corresponding vibrations in the diaphragm 17 of the microphone, which is arranged directly opposite the diaphragm 12 and the 90 vibrations of the diaphragm 17 cause corresponding variations of the resistance of the current paths from the carbon block 19 through the material 22 to the diaphragm 17. These variations of resistance cause 95 corresponding variations of the current flowing in the circuit from the binding-post 44 to the microphone by wire 46, then to the switch 37 by wire 47 and through the battery to the binding-post 43. These binding- 100 posts 43 and 44 may have a low resistance telephone receiver 48 connected thereto by wires 49, this receiver 48 being preferably provided with a sound amplifier of substantial size. By turning the switch arm 36 so 105 as to contact with either stud 39 or stud 40, either two or three of the cells of the battery may be connected in the circuit of the microphone and a current strength thus obtained which is found to give the best results. Also the pivotal mounting of the 110 combined telephone receiver and microphone permits of adjusting those parts to the angular position which makes the apparatus most sensitive under the conditions 115 prevailing. When the angular position of the microphone is changed the particles of conducting material in the cups formed in the carbon block move to a new level depending upon the extent of angular movement of the microphone so that a greater or less number of the particles are in contact with the diaphragm 17 and the vibrations of the diaphragm are thus made more or 120 less effective. In practice, the angular position of the microphone and telephone which makes the apparatus most sensitive may be readily found. With this apparatus, therefore, sounds which would be very feeble if 125 produced by a telephone receiver in the cir- 130

cuit of the wires 9 and 10 and which would require that the receiver be held close to the ear, may be amplified so as to permit of hearing them quite readily at a substantial 5 distance from the amplifier of the receiver 48.

The apparatus herein described possesses the further advantage that it is much more sensitive to current of relatively high frequency as a result of which it aids in preventing interference caused by static and other low frequency disturbances. 10

I claim:

1. A receiving apparatus comprising the combination of a receiving circuit, a telephone receiver connected thereto, a microphone including granular material mounted opposite said receiver, means for varying the angular position of the microphone 15 whereby the degree of conductivity of the microphone is varied and a battery and a telephone receiver connected in circuit with the microphone, substantially as described.
2. A receiving apparatus comprising the combination of a receiving circuit, a telephone receiver connected in said circuit, a microphone including granular material 20

secured to said receiver, means for effecting angular adjustment of the receiver and microphone whereby the degree of conductivity of the microphone is varied and a battery and a telephone receiver connected in circuit with the microphone, substantially as described. 30

3. A receiving apparatus comprising the combination of a receiving circuit, a telephone receiver connected therein, a microphone including granular material, means for securing the receiver and microphone together with their diaphragms opposite each other and a closed chamber between the diaphragms, means for pivotally mounting the combined receiver and microphone and permitting angular adjustment thereof whereby the degree of conductivity of the microphone is varied and a battery and telephone receiver connected in circuit with the microphone, substantially as described. 35 40 45

In testimony whereof I affix my signature, in presence of two witnesses.

ALFRED H. GREBE.
